UNITED STATES PATENT OFFICE.

ELZEAR O. LA FRANCE, OF WORCESTER, MASSACHUSETTS.

LOOM.

1,209,173.

Specification of Letters Patent. Patented Dec. 19, 1916.

Application filed March 1, 1916. Serial No. 81,311.

To all whom it may concern:

Be it known that I, ELZEAR O. LA FRANCE, a citizen of the United States, residing at Worcester, in the county of Worcester and 5 Commonwealth of Massachusetts, have invented a new and useful Improvement in Looms, of which the following is a specification, accompanied by drawings forming a part of the same.

10 The present invention contemplates the provision of a loom capable of simultaneously weaving a plurality of separate fabrics without interference, and in such a manner that the threads of both fabrics will 15 be fully and completely exposed at the front of the loom, for inspection and repair by an operator stationed in the usual position.

20 My invention embodies various features of novelty in connection with the attainment of the above described objects, all of 25 which are fully set forth in the following description and illustrated in the accompanying drawings, wherein—

Figure 1 is a front view of my improved 30 loom. Fig. 2 is a side view thereof. Fig. 3 is a longitudinal sectional view. Fig. 4 is a fragmentary view of a portion of the operating mechanism of the loom.

Like reference characters refer to like 35 parts in the different figures.

The reference numerals 1, 1, represent the framework of the loom, which supports a transverse crank shaft 2. At the rear of the framework are journaled lower and upper 40 yarn beams 3 and 4. The warp threads from the lower yarn beam 3 pass through the usual heddles, not shown, of lower harness frames 5, 5, and thence over lower breast beam 6; the warp threads from the upper yarn beam 4 pass through the heddles of upper harness frames 7, 7, and thence over breast beam 8 at the front of the loom.

45 The corresponding members of the upper and lower pairs of harness frames for the two sets of warp threads are connected by straps 9, 9. A pair of straps 10, 10, attached to the upper sides of the frames 7, 7, pass over loose pulleys or the like 11, 11, suitably supported by the arch of the frame 1. The harness frames, thus connected, are operated by any well known means, as by a pair of 50 vibrating levers 12, 12, each connected to one of the lower harness frames 7, 7, by a strap 13, and actuated by means of suitably shaped cams 14, 14, on the driving shaft 15,

which is connected by gearing 16, 17, to the crank shaft 2.

The reference numeral 18 designates as a whole, the lay, which is made in upper and lower parts, as hereinafter described, 60 for the weaving of the upper warp threads into a fabric, and the lower part providing a shuttle race 20 for the weaving of the lower warp threads into another fabric. At 65 the rear of the race 20 the lower part 21 of the lay, which is pivoted at 22, provides the usual reed 23; at the rear of the race 19 the upper part 24 of the lay, which is pivoted at 25 to the lower part, provides the 70 reed 26. A pair of links 27 connect the lower part 21 of the lay to cranks 28 on the shaft 2, thus providing for the vibration of the lay 18 in the usual manner. A pair of links 29 also connect the lower part 21 75 to a pair of racks 30 supported for sliding movement in the framework; the reciprocation of these racks, due to the vibration of the lay imparts a predetermined rotation in each direction to the pinions 31 associated 80 with said racks 30. In turn, the rotation of the pinions 31 is imparted to upper sliding racks 32, which of course move in directions opposite to the racks 30. Said racks 32 are connected by links 33 to the ends of 85 levers 34, pivoted at 35, upon the stationary framework. The other ends of said levers are connected by links 36 to the upper part 24 of the lay.

In the operation of the lay 18, constructed as above described, the amplitude of vibration of the lower shuttle race 20 is dependent on the throw of the cranks 28. By reason of the connected mechanism consisting of the racks 30 and 32 and lever 34 the 90 amplitude of vibration of the upper shuttle race 19, instead of being much greater than that of the lower race, as would be the case if the lay 18 were a rigid structure, is made substantially the same as that of the lower race, said connected mechanism constituting 95 in effect a parallel motion. That is, said connected mechanism so vibrates the part 24 about its moving pivot 25 that the upper shuttle race 19 is always maintained substantially perpendicularly above the lower shuttle race 20, and thus has imparted thereto the same throw.

For operating the shuttle, not shown, of the lower shuttle race, picker-sticks 37, 37, 110

are provided, while for the upper race, picker-sticks 38, 38, are provided. These sets of picker-sticks are pivoted at 39, 39, on opposite sides of the loom, and each pair 5 37, 38, is actuated in unison by means of cranks 40, 40 formed on rock shafts 41, 41, to which they are attached by means of links or straps 42, 42, or any other suitable connecting means. The shuttles of the upper and lower races are thus caused to move 10 in the same directions at the same time. Each rock shaft 41 has attached thereto an arm 43, the other end of which is held against the periphery of a cam 44, on shaft 15 15, by means of springs 45, acting on said picker-sticks.

The operation of the mechanism hereinbefore described will be clear to those conversant with the operation of looms; it being obvious that I have made provision for 20 the weaving of two separate fabrics, by the coöperation of the usual mechanism, in the manner well known to those skilled in the art. Any of the ordinary appurtenances 25 which are provided in looms for the weaving of a single fabric are equally applicable to both the upper and the lower portions of my improved loom; for instance, the usual mechanism for stopping the operation of 30 the machine, upon the breaking of a thread may be readily applied to each part of the present loom, the same being herein illustrated diagrammatically for the sake of clearness, by the stop motion levers 46, 46, 35 which may be actuated by cams 47, 47, on the shaft 15.

The fabric woven by the lower part of the loom passes from the breast beam 6 over a roller 48 and is wound in the usual manner 40 upon a take-up roll 49, driven by gearing 50, 50, from an intermittently rotated sprocket 51, having an actuating eccentric 52 on the shaft 2. The take-up roll 49 is located in the same relation to the breast beam 6 as in 45 an ordinary single fabric loom. If, however, the take-up roll for the upper fabric were located in the same relation to the upper breast beam 8, said roll and the fabric being wound thereon would not only ob- 50 struct the operator's view of the lower fabric, but would prevent his access thereto for the purpose of repairing or adjusting the threads thereof.

According to my invention the woven upper fabric is led around a roller 53, and thence rearwardly of the machine to a take-up roll 54, driven by gearing 55, 55, from an intermittently rotated sprocket 56, having an actuating eccentric 57 on the shaft 2. 55 The weaving of the lower fabric is thus exposed to the full view of the operator at the front of the machine and all of the operating mechanism for this lower fabric is readily accessible.

65 The upper fabric, as above described is led

rearwardly so as not to be superposed upon the lower fabric; the weaving of this upper fabric, at the rear of the breast beam 8, is brought into the full view of the operator, standing at the front of the loom, by means of a mirror 58, adjustably mounted on trun- 70 nions 59 above said fabric, and in the line of vision of the operator, who is thus enabled to watch the weaving of both fabrics without changing his position.

I am aware that looms for the weaving of a plurality of fabrics, one above the other, have been heretofore proposed, and I therefore make no claim broadly to such construction; my invention resides in the arrangement of parts whereby the weaving of the lower fabric is not obscured, and in the introduction of the several changes in the operating mechanism which renders the above result possible.

I claim:

1. In a loom, a pivoted lay, means for os- 90 cillating said lay about its pivotal axis, said lay providing a plurality of superposed reeds, and mechanism operatively connected to each reed for equalizing the movement of said reeds in the vibration of said lay.

2. In a loom, a pivoted lay, means for os- 95 cillating said lay about its pivotal axis, said lay providing a reed for a lower fabric and an independent reed for an upper fabric, and mechanism operatively connected to each reed for maintaining said reeds sub- stantially in vertical alinement.

3. In a loom for weaving simultaneously 100 an upper and a lower fabric, a pivoted lay common to both fabrics, means for oscillating said lay about its pivotal axis, said lay having two sections, one for each fabric, and means for equalizing the movement of the 105 sections of said lay.

4. In a loom, a lay providing a lower reed and an upper reed, means for vibrating said lay to move said lower reed in a path of predetermined amplitude, and means actuated by the vibration of said lay for limiting the movement of the upper reed to a path of the same amplitude as the lower reed.

5. In a loom, a lay consisting of two 115 hinged sections, each section providing a reed, means for vibrating one section, and means actuated by the vibration of the first section for maintaining the reed of the sec- ond section in a path of the same amplitude 120 as the reed of the first section.

6. In a loom for the weaving of two fab- 125 rics, one above the other, a breast-beam over which the woven upper fabric is drawn, and a take-up roll for said woven upper fabric disposed rearwardly of said breast-beam, whereby the weaving of the lower fabric is visible from the front of the loom.

7. In a loom for the weaving of two fab- 130 rics, one above the other, means for revers-

ing the direction of the upper woven fabric above the plane of the weaving of the lower fabric, whereby the weaving of said lower fabric is visible from the front of the loom.

8. In a loom for the weaving of two fabrics in upper and lower horizontal planes, means for directing the woven upper fabric rearwardly in a plane between the planes of weaving of the two fabrics, whereby the weaving of the lower fabric is visible from the front of the loom.

9. In a loom for the weaving of two fabrics in upper and lower horizontal planes,

means for directing the woven upper fabric rearwardly in a plane between the planes of weaving of the two fabrics, whereby the weaving of the lower fabric is visible from the front of the loom, and a mirror above the plane of weaving of the upper fabric, whereby the weaving of said upper fabric is visible from the front of the loom.

ELZEAR O. LA FRANCE.
